UNITED STATES PATENT OFFICE.

ARTHUR D. LORD, OF CHICAGO, ILLINOIS.

COMBINED STATEMENT AND ENVELOP.

No. 821,723.

Specification of Letters Patent.

Patented May 29, 1906.

Application filed February 8, 1906. Serial No. 300,096.

To all whom it may concern:

Be it known that I, ARTHUR D. LORD, a citizen of the United States, residing at Chicago, in the county of Cook and State of Illinois, have invented a certain new and useful Improvement in a Combined Statement and Envelop, of which the following is a full, clear, concise, and exact description.

My invention relates to a combined statement-blank and envelop, and its object is to provide a statement-sheet or similar device which can be folded into the form of an envelop to utilize the superscription of the statement as the address of the envelop and which can readily be opened, leaving the statement in the usual form.

My invention contemplates a sheet having wings upon each side at its lower portion and provided with perforations in alignment with edges of the upper half of the sheet. The extreme lower part of the sheet comprises a flap having a portion cut out so that when the sheet is folded in the form of an envelop the name and address of the person to whom the statement is rendered is visible.

In my invention when the sheet is doubly folded at the center the lower half thereof incloses the upper half and each side wing is folded upon itself. The envelop may then be sealed by merely securing together said folded parts of the wing by adhesive material affixed thereto or in any other suitable manner. The envelop is readily opened by tearing off said wings along the lines of perforations. This provides a quick and easy means of opening the envelop and also leaves the statement-sheet in the usual form.

My invention may be readily understood by reference to the accompanying drawings, 40 in which—

Figure 1 is a plan view of the sheet in its unfolded condition. Fig. 2 is a view showing the sheet folded in the form of an envelop. Fig. 3 is a perspective view showing 45 the method of folding the sheet.

Similar letters of reference refer to similar parts throughout all the figures.

The lower part of the statement-sheet is provided with side wings *a b* and a flap *c*. 50 Said flap is likewise provided with wings *a' b'*, forming continuations of the wings *a b*, respectively. The flap *c* is cut out so that when the sheet is folded, as shown in Fig. 2, the name and address of the party to whom 55 the statement is made out is rendered visible

and constitutes the address upon the envelop.

To form the envelop, (shown in Fig. 2,) the sheet is doubly folded in its center, as indicated in Fig. 3. The upper half of the sheet 60 is thus inclosed by the lower half and the wings *a' b'* lie upon the wings *a b*, respectively, upon each side of the upper portion of the sheet. By coating said wings with adhesive material said parts *a' b'* may be readily secured to the parts *a b*, respectively, thus 65 securely sealing the envelop. Lines of perforations *a² b²* are preferably provided at each side of the sheet in alignment with the edges of the upper portion thereof. To open the 70 envelop, it is merely necessary to tear off the wings along said perforations. The flap *c* is also preferably separated from the statement-sheet *A* by a perforated line in order that it may be readily torn off after the 75 envelop is opened. By placing the postage-stamp in the position indicated in Fig. 2 said stamp may also be utilized in holding the flap *c* against the face of the statement, and thus prevent the withdrawal of the upper part of 80 the sheet from its inclosing pocket.

My invention provides a statement of cheap manufacture that can be readily folded into an envelop, thus not only saving the cost of the envelop, but the time and labor incidental to addressing the same. In sealing the envelop it is necessary to fold under the wings, the usual folding of the sheet sufficing to bring the parts in proper sealing position. Moreover, the statement is uninjured in opening the envelop, for when torn along the lines of perforation the usual statement-blank is left intact. When canceled in the usual manner by the post-office, the date of transmission is placed on the face of the 90 sheet, and the customary receiving-stamp when applied to the back of the envelop becomes thereby a record upon the back of the statement showing the date of its receipt.

Having thus described my invention, I claim—

A sheet of paper comprising a statement-head and a statement-body, the lower half of the statement-body being provided upon each side with wings and at its end with a flap, said flap having wings forming continuations of the wings of the statement-body, said flap being adapted to be folded upon the lower portion of the statement to inclose the folded upper portion of the sheet, said wings of the 110

flap overlying the wings of the statement and adapted to be secured thereto outside the edges of the inclosed portion of the sheet, and said flap being substantially U-shaped with the opening of the U at the end of the flap; whereby the superscription at the head of the statement is rendered visible and constitutes the address of the folded statement, and a postage-stamp upon the face thereof may be utilized for sealing the inner folds of the

sheet from withdrawal from the inclosing outer folds.

In witness whereof I hereunto subscribe my name this 5th day of February, A. D. 1906.
